(57) **CLAIM**

The ornamental design for a suction cup mount, as shown and described.

DESCRIPTION

FIG. 1 is a top and left side perspective view of a suction cup mount in a folded and locked and unrotated configuration showing our new design;

FIG. 2 is a top and right side perspective view thereof;

FIG. 3 is top plan view thereof;

FIG. 4 is a bottom plan view thereof;

FIG. 5 is a rear elevational view thereof;

FIG. 6 is a front elevational view thereof;

FIG. 7 is a left side elevational view thereof;

FIG. 8 is a right side elevational view thereof; and

FIG. 9 is a top and and left side perspective view of a suction cup mount in an unfolded and locked and unrotated configuration.

FIG. 10 is top and right side perspective view thereof.

FIG. 11 is a top plan view thereof.

FIG. 12 is a front elevational view thereof.

FIG. 13 is right side elevational view thereof.

FIG. 14 is right side elevational view of a suction cup mount in an unfolded and unlocked configuration.

FIG. 15 is a top and right side perspective view thereof.

FIG. 16 is top and left side perspective view of a suction cup mount in a folded and locked and rotated configuration;

FIG. 17 is a top plan view thereof; and,

FIG. 18 is a top and right side perspective view of a suction cup mount in an unfolded and locked and rotated configuration.
